UNITED STATES PATENT OFFICE.

REID J. McCREDIE, OF BUFFALO, NEW YORK.

RADIATOR.

1,407,554.

Specification of Letters Patent. Patented Feb. 21, 1922.

Application filed June 16, 1919. Serial No. 304,516.

To all whom it may concern:

Be it known that I, REID J. McCREDIE, a citizen of the United States, residing at Buffalo, in the county of Erie, in the State 5 of New York, have invented certain new and useful Improvements in a Radiator, of which the following is a specification.

This invention relates to improvements in radiators of the type ordinarily employed 10 in connection with the water cooling systems for the engines of motor vehicles and the invention has for its object to generally improve and simplify this type of radiator by the provision and utilization of a novel 15 type of vertical water tube constructed of sheet metal and provided with a series of fins for increasing the heat radiating surface of the tube and causing the rapid cooling of the liquid passing therethrough.

20 Another object is the provision of a novel type of coupling connecting the terminals of the tubes with the upper and lower water containing elements of the radiator whereby the tubes may be quickly and conveniently 25 removed for repair or replacement, and in case of emergency.

With these and other objects in view as will appear as the description proceeds the invention comprises the novel features of 30 construction, combination of elements, and arrangement of parts which will be more fully described in the following specification as set forth with particularity in the claims appended hereto.

35 Figure 1 represents a vertical central sectional view through the improved radiator.

Figure 2 represents a plan view of one terminal of one of the water tubes and the clamping plate therefor, the same being re- 40 moved from the radiator.

Figure 3 represents a fragmental longitudinal sectional view through the terminal of one of the tubes.

Figure 4 is a transverse sectional view 45 through the tube taken at right angles to Figure 3, and,

Figure 5 represents a fragmentary perspective view of one of the nut retaining plates of the radiator structure.

50 Referring to the drawings in detail, wherein similar reference characters designate corresponding parts throughout the several views, the numerals 5 and 6 indicate generally the upper and lower members of the radiator which are of hollow formation 55 providing the internal water chambers for

the reception of the water or other liquid to be utilized in cooling the explosive engine (not shown) in connection with which the radiator is used. The lower member 6 60 is formed centrally with an aperture communicating with a discharge coupling 7 which is adapted for connection with a hose or other hollow member whereby the cooled water is conducted from the lower portion 65 of the radiator back to the water jacket of the engine. The lower hollow member 6 is preferably constructed of two strips of sheet metal substantially L-shaped in cross section and having the adjacent edges interlocked 70 as indicated at 8 and soldered or otherwise connected so as to form a rigid and fluid tight joint preventing leakage of the liquid contents of the member and maintaining the member in proper form. 75

The upper member 5 is preferably constructed of a plurality of strips of sheet metal having the adjacent edges interlocked as indicated at 9 and provided in the rear wall thereof with an aperture communicat- 80 ing with a coupling 10 adapted for connection with a hose or other hollow member whereby the heated water from the water jacket of the explosive engine is conducted to the upper portion of the radiator. The 85 opposite extremities of the upper and lower members 5 and 6 are connected by the vertically disposed side members 11 maintaining the top and bottom members in properly spaced relation and increasing the strength 90 and rigidly of the entire radiator structure. The top member is further provided with a filling spout 12 carrying a removable top 13.

The top and bottom members are connected, intermediate the side members 11, by 95 a series of vertical water tubes designated generally by the numerals 14 and each of which is constructed of a single piece of sheet metal doubled along a longitudinal line as indicated at 15 and having the longi- 100 tudinal edges interlocked as indicated at 16 and soldered or otherwise secured together to render the joint fluid tight. As will be understood, the side members of the tubes are arranged in spaced relation to provide 105 a water passage. The opposite terminals of each tube are flanged as indicated at 17 to engage the bottom of the top member 5 and the top portion of the bottom member 6.

Clamping or coupling plates 18 having 110 elongated openings are movably engaged upon the opposite terminals of each tube 14

inwardly of the flanges 17 thereof, and the extremities of the clamping plates are apertured to receive bolts 19 which extend through the upper and lower members 5 and 6 and are engaged with bars 20 whereby the clamping plates are brought in clamping relation with the flanges 17 to snugly clamp the latter in engagement with the top and bottom radiator members and establish a fluid tight connection therewith. The top and bottom members 5 and 6 are provided with a series of apertures registering with the tubes 14 permitting a free circulation of liquid between the hollow members and tubes, and flanges 21 are preferably formed at the edges of the openings in the top and bottom members to strengthen and reinforce the radiator structure. Angular covering members 22 are secured in any suitable manner internally of the upper and lower members 5 and 6, to protect the bars from the water and prevent them from rusting and being otherwise deteriorated. The intermediate portion of each water tube is formed with staggeredly arranged and reversely corrugated portions 23 providing a zig-zag passage throughout the major portion of the length of the tube to increase the heat radiating surface thereof and accelerate the cooling of the liquid passing therethrough. To further increase the cooling efficiency of the radiator each tube is preferably provided with a series of parallel

fins 24 projecting laterally of the opposed side walls thereof, the fins on one side of the tube being arranged in staggered relation to those of the opposite side.

The bars 20, being arranged internally of the upper and lower members 5 and 6, materially increase the strength and rigidity of the entire radiator structure, and by the utilization of the angular retaining strips 22 the bars are not only held in adjusted position but are also respectively protected against the rusting and corrosive action of the cooling liquid contained within the radiator.

What I claim is:

1. A radiator formed of a plurality of water columns of zig zag formation vertically, and a plurality of air dividing vertical wings extending from opposite sides of each of said columns and in spaced relation from front to rear. 55

2. A radiator comprising upper and lower chambers, and a plurality of water circulating columns communicating with the chambers, each of said columns being formed of zig zag formation vertically, and with a plurality of air dividing vertical wings extending from opposite sides of each of said columns, and in spaced relation from front to rear. 60

In testimony whereof, I affix my signature hereto. 65

REID J. McCREDIE.
